UNITED STATES PATENT OFFICE.

JEAN SCHELUTO AND FERNAND JULIEN JOSEPH FURNEMONT, OF BRUSSELS, BELGIUM; SAID SCHELUTO ASSIGNOR TO GASTON EMILE COENE, OF UCCLE, NEAR BRUSSELS, BELGIUM.

MEANS FOR REGULATING AUTOMATICALLY SWEEPING FIRE IN MACHINE GUNS.

Application filed August 20, 1925, Serial No. 51,468, and in Belgium August 29, 1924. Renewed November 10, 1926.

This invention has for its object the provision of means for automatically regulating "sweeping" fire in machine guns which is controlled by the impulse of the recoil mechanism under the action of the gases of propulsion. For application to machine guns enables at all distances the same space to be obtained between the projectiles.

This arrangement carried by the machine gun properly speaking, comprises an arrangement of levers connected at one part to the axis of the operating lever and at another part to a ratchet wheel the movement of which controls the lateral displacement of the gun by the intermediary of gearing.

The useful length of one of the levers is variable in order to enable the angle of displacement of the ratchet wheel to be varied to regulate in this manner the successive traverses of the gun.

The meshing gearing controlled by the ratchet wheel is adapted to the construction of the gun. In a Maxim gun, this ratchet wheel may be supported on a worm which engages with a double toothed sector rotatable on a platform supported by the gun, the said sector in turn engaging with a simple toothed sector fixed to the cradle of the gun.

In the accompanying drawings one form of carrying the invention into effect is shown by way of example:

Fig. 1 is an elevation of a Maxim machine gun with its carriage support and

Fig. 2 is a plan of the arrangement, the machine gun being indicated in broken lines.

On the pivot of the operating lever mounted on the axis of the cranked trunnions of the recoil mechanism is fixed a button A which receives a rod B which is carried at its other end by a lever C.

According to the form shown in the drawings, the lever C is in the form of a V and pivoted at its angle to a support R fixed to the gun body. One of the branches of the lever is perforated in order that another rod D may be attached thereto of varying heights such rod D being in turn connected to a handle F, freely pivoted on the end of a worm N and carrying a pawl T which engages with a ratchet wheel G.

The connection of the rod D to the lever

C may be made by means of a member slideable on the said lever or alternatively by a threaded sleeve adjustable on the arm of the lever in this case constituted by a threaded stem provided with a controlling hand wheel; in this latter case the turning movement of the threaded stem operates to adjust the position of the threaded sleeve and the point of attachment of the rod D. In mechanical design various constructions are known for varying the position of the point of attachment of a connecting rod, and any of these devices may be adapted for coupling the rod D to the lever C.

The worm turns between and is mounted in two supports E which are secured to the gun body first by a pivot K and also by an adjustable screw S which allows the worm N normally to engage with the rear end of a double toothed sector I. This double sector turns freely on a small platform H fixed to the gun body and whilst one of its ends engages with the worm N, the other is in engagement with a fixed toothed sector J which is fixed to the cradle M of the gun.

L represents the carriage, P the horizontal trunnions carrying the cradle and Q the vertical trunnions supporting the barrel of the gun.

The operation of the arrangement forming the subject of the invention is as follows:—

The axis of the cranked trunnions of the recoil mechanism in the case of the Maxim gun for example accomplishes between two transverses of fire an alternate rectilinear movement. The pivot A mounted on this axis follows therefore the same movement.

The handle F connected to the point A by the levers B, C and D describes therefore an arc of a circle and according as the pawl T is turned in one direction or the other, the ratchet wheel G rotates in one direction or the other.

The worm N being fast with the ratchet wheels G turns also in the one or the other direction, the worm N being maintained in place by the supports E and engaging with the double sector I which pivots on the plate H. This sector is compelled to become displaced in a given direction and to displace the axis of the gun since the double sector I is engaged by the sector J which is

fixed to the cradle; the gun is thus compelled to follow the movements of the sector I as it is pivoted horizontally by the trunnions Q turning in the cradle M which is itself 5 fixed to the carriage L. The same result will be obtained. By omitting the double sector and in placing the sector J in direct engagement with the worm N.

For different distances, the angle of 10 placement must be different and is obtained by changing the position of the point of attachment of the rod D to the lever C.

To free the gun from the device it is necessary to loosen the screws S and to rock 15 the members E thus bringing the worm N out of engagement with the sector.

The arrangement above described may be applied to all types of machine guns wherein there is gas operated recoil mechanism, it 20 being necessary only to vary the method of attachment of the apparatus.

A mechanism allowing an alternative to-and-fro movement to the double sector I may be provided and further the invention 25 is not limited to the details described as numerous modifications may be made in its details without departing from the spirit of the invention.

We claim:—

30 1. Means for regulating automatically "sweeping" fire in machine guns comprising recoil mechanism, gearing for traversing the gun, links connecting said recoil mecha-

nism and traversing gear and means for adjusting the relative positions of said links, 35 which traversing gear includes a ratchet wheel, a worm rotated by said ratchet wheel, a double toothed sector engaging said ratchet wheel and pivoted on the gun base, and a single toothed sector engaging said 40 first named sector and fixed to the cradle of the gun.

2. Means for regulating automatically "sweeping" fire in machine guns comprising recoil mechanism, a worm, means for rotating said worm from said recoil mechanism, a double toothed sector pivoted to the base of the gun and meshing at one end with said worm, a toothed sector fixed to the 45 cradle of the gun and also meshing with said worm and means for varying the degree of rotation of said worm.

3. Means for regulating automatically "sweeping" fire in machine guns comprising recoil mechanism, a series of links extending therefrom, means for varying the effective length of one of said links, a ratchet wheel, means for rotating said ratchet wheel operated by said links, a worm rotatable with said ratchet wheel, a double sector having teeth at each end and meshing with said worm, a fixed pivot for said sector and a toothed sector meshing with said double sector and fixed to the cradle of the gun. 55
